DANIEL S. COLBY AND ROBERT SCORER, OF TROY, NEW YORK, ASSIGNEE
TO EDWARD J. HICKS AND GURDON G. WOLFE, OF SAME PLACE.

Design No. 2,965, dated March 31, 1868.

DESIGN FOR A STOVE-URN.

The Schedule referred to in these Letters Patent and making part of the same.

TO ALL WHOM IT MAY CONCERN:

Be it known that we, DANIEL S. COLBY and ROBERT SCORER, each of the city of Troy, in the county of Rensselaer, and State of New York, have jointly invented or produced a new and original Design for Stove-Urns, of which the following is a full and exact description, reference being had to the accompanying photograph of a stove-urn having our said design.

This design for stove-urns consists of spreading leaves *a* on the base; spreading, compound, scroll-leaf on the body; and open-work top *c c c*, all shaped and combined so as to appear as represented in the aforesaid photograph.

What we claim as new and of our invention or production, and desire to secure by Letters Patent, is—
The design for stove-urns, herein set forth and shown.

In testimony whereof, we have hereunto set our hands, this 11th day of February, 1868.

DANL. S. COLBY,
ROBERT SCORER.
